(57) **CLAIM**

We claim the ornamental design for a booth, as shown and described.

DESCRIPTION

FIG. 1 is a front perspective view of a booth showing a first embodiment of our new design;

FIG. 2 is a rear perspective view thereof;

FIG. 3 is a front view thereof;

FIG. 4 is a rear view thereof;

FIG. 5 is a side view thereof;

FIG. 6 is a side view of the opposite side of FIG. 5;

FIG. 7 is a top view thereof;

FIG. 8 is a front perspective view of a booth showing a second embodiment of our new design;

FIG. 9 is a rear perspective view thereof;

FIG. 10 is a front view thereof;

FIG. 11 is a rear view thereof;

FIG. 12 is a side view thereof;

FIG. 13 is a side view of the opposite side of FIG. 12;

FIG. 14 is a top view thereof;

FIG. 15 is a front perspective view of a booth showing a third embodiment of our new design;

FIG. 16 is a rear perspective view thereof;

FIG. 17 is a front view thereof;

FIG. 18 is a rear view thereof;

FIG. 19 is a side view thereof;

FIG. 20 is a side view of the opposite side of FIG. 19;

FIG. 21 is a top view thereof;

FIG. 22 is a front perspective view of a booth showing a forth embodiment of our new design;

FIG. 23 is a rear perspective view thereof;

FIG. 24 is a front view thereof;

FIG. 25 is a rear view thereof;

FIG. 26 is a side view thereof;

FIG. 27 is a side view of the opposite side of FIG. 26; and,

FIG. 28 is a top view thereof.

(Continued)

The broken lines shown in the drawings illustrate portions of a booth that form no part of the claimed design.
